KNOT TYING

Martin N. Noling, Rockford, Ill., assignor to
 Barber-Colman Company, Rockford, Ill., a corporation of Illinois

Application December 17, 1938, Serial No. 246,337

6 Claims. (Cl. 289—1)

The invention pertains to knot tying and has particular reference to an improved method of tying knots as well as to an apparatus for carrying out such method.

The present invention finds particular utility as applied to the knotting of threads or yarns made of silk, rayon, celanese or other regenerated cellulose derivatives. Such threads or yarns are hard and unyielding as compared, for example, to cotton, and as a consequence it is difficult to tie knots in them in tying in a new warp, for instance, which will not be shaken loose as the threads are pulled and jerked in subsequent movements through the reeds and harness of a loom. The general aim of the present invention is to overcome this difficulty by providing an improved method, as well as an apparatus for carrying out the same, for knotting threads or yarns which is capable of forming a firm hard knot in threads or yarns made of even such materials as silk, celanese, rayon or other regenerated cellulose derivatives. This object is, in general, accomplished by moistening the portions of thread which are included in the knot, preferably during the completion of the knot, so that when the knot dries the threads take on a permanent hard "set" in their knotted form.

A more specific object of the invention is to provide a knotter in which the knotted ends of the thread or yarn are moistened as an incident to their movement in the knot tying operation so that a firm hard knot results which will readily withstand jerking and pulling such, for example, as that which is encountered in a weaving operation.

Further objects and advantages of the invention will become apparent as the following description proceeds, taken in connection with the accompanying drawing in which:

Figure 1 is a general perspective view of a warp tying machine, including a knotter embodying the present invention and adapted to carry out the improved method herein disclosed.

Fig. 2 is an enlarged detail front elevation of the knotter included in the apparatus of Fig. 1 showing in particular the movement of the knotted thread ends across a moistening wick during their removal from the knotter.

Fig. 3 is a detail side elevation, partly in section, of the knotter shown in Fig. 2.

The invention has been shown and described herein as applied to the tying of an ordinary round knot to unite a pair of threads but it will be understood that the invention is also appli-

cable to the tying of other types of knots such, for example, as a weaver's knot. Also, the invention has been shown and described herein as embodied in a knotter of a warp uniting machine of the general type shown in Peterson Patent No. 2,011,115, but it is also applicable to hand knotters or knot tying devices included in other types of warp-uniting machines.

In order to make clear the practice of the invention a particular application and embodiment thereof have been shown and described herein in some detail but there is no intention to thereby limit the invention to such application and embodiment, but, on the other hand, the appended claims are intended to cover all modifications and alternative constructions falling within the spirit and scope of the invention.

As was noted above the invention has been shown herein (Fig. 1) as embodied in a knotter for a warp tying machine of the type disclosed in said Peterson Patent No. 2,011,115. This machine is designed in general to select successive pairs of threads from an old warp A and a new warp B, to segregate the threads from the respective warps to make up successive pairs, tie the successive pairs of threads together, and cut off and dispose of the waste end portions. For this purpose the machine is provided with a selector mechanism (not shown) for segregating successive threads *a* and *b* from the respective warps A and B after which a mechanism including a reciprocable slide 10 serves to advance the segregated threads to a knotter, shown as including a rotating tying bill 11. The successive selected pairs of threads are pushed together for tying and positioned in operative relation with the tying bill 11 by means including a pair of guides designated generally by the numerals 12 and 13, which are located on opposite sides of the bill. The guide 12 is of fork shape and the threads *a*¹—*b*¹ are pushed into its narrowest throat portion to locate the same for tying by the bill 11. The guide 13 is also of a generally fork shape but is provided with barbs 13^a thereon which prevent the threads from springing back out of the fork.

The particular form of knot tying mechanism shown herein is similar to the one fully disclosed in Colman Patent No. 1,082,474 issued December 23, 1913. In general, it includes a rotatable tying bill 11, rotated by means of a spiral gear 14 meshing with gear 15. This gear 15 is driven, through suitable intermediate gearing, by a main drive gear 16 which also serves to reciprocate

not only the slide 10 but also the stripper and waste end disposal mechanism.

Rotation of the tying bill 11 causes it to engage the threads a^1 and b^1 and entwine them into the form of a loose round knot. The knot, which is loosely formed by the tying bill 11, is pulled tight and stripped from the bill by a notched rotating stripper disk 17. The threads a^1-b^1 are lodged within a notch 17a in the stripper and it is rotated in timed relation with the movement of the tying bill 11 so that the threads are pulled down by the stripper between a pair of plates 18-18a (Fig. 2) to strip them from the tying bill.

The warp threads are supported in the machine by suitable clamps 19-20 on opposite sides of the knotter, only the clamps at the right hand side being herein shown. At the completion of the tying operation the threads are sheared at the tying bill and at a point adjacent the selector mechanism by a shear means (not shown) leaving waste ends for removal by means designated generally by the numeral 21.

In accordance with the present invention the knotted ends of the threads a^1-b^1 are moistened and this moistening operation is preferably carried out by moving them across a source of moisture as an incident to the stripping of the knot from the tying bill 11. For this purpose a sheet metal cup 22 (Fig. 2) is fixed to the upper side portion of the plate 18 so that one end of a wick 23 disposed within the cup lies flush with the top of the plate. The outer side wall of the cup is located below the upper edge of the plate 18. Consequently, when the stripper 17 pulls the knotted threads over the edge of the plate 18 it also pulls them across the exposed top of the wick 23 so that they are saturated with moisture from the wick. The wick 23 itself is kept moist by immersing one end thereof in a reservoir 24 filled with water (Fig. 3). After the threads leave the knotter they become dry in a short time by their exposure to air and the previously wetted knot takes on a hard permanent set. Consequently, the ends of the threads will not be pulled apart by the jerking and pulling of the reeds and harness in the loom during subsequent weaving operations even though the threads be made of such hard unyielding materials as silk, celanese, rayon or other regenerated cellulose derivatives.

I claim as my invention:

1. In a knot-tying mechanism, the combination of, means including a rotatable tying bill for knotting the ends of a pair of threads, a plate presenting an edge to the threads at a point ad-

jacent said tying bill, a stripper movable along the face of said plate opposite said tying bill past said edge thereof and engageable with the threads to pull the same from said tying bill and across said plate edge, means including a wick located adjacent said plate edge for wetting the knotted portion of the threads as it is pulled across the same by said stripper, and means for supplying liquid to said wick.

2. In a knot-tying mechanism, the combination of, means including a rotatable tying bill for knotting the ends of a pair of threads, a stripper for pulling the knotted threads from said tying bill, and means for moistening the knotted portion of the threads during their movement by said stripper.

3. A knotter of the type embodying a rotating tying bill for knotting two portions of thread or the like, characterized by the provision of means for moistening such portions of thread as an incident to their movement during the knot tying operation.

4. In a knot-tying mechanism the combination of means including a rotatable tying bill for knotting the ends of a pair of threads, a pair of spaced plates presenting edge portions thereof to the threads adjacent said tying bill, a stripper movable between said plates past the edge portions thereof and engageable with the threads to pull the same from said tying bill and into the space between said plates across said edges thereof, a liquid reservoir, a wick projecting from said reservoir, and means including a cup located adjacent one of said plate edges for supporting a portion of said wick to wet the knotted portion of the threads as it is pulled across the same by said stripper.

5. The method of knotting threads prior to their utilization in a textile weaving operation or the like, which comprises, intertwining in the form of a loose knot portions of a pair of threads to be united, exerting a pulling force on the threads to draw the knot tight; and, as an incident to the movement resulting from such pulling, moving the threads across a source of moisture to wet the same.

6. The method of uniting the ends of a pair of threads securely together so as to prevent their disjoining due to subsequent pulling or jerking, which comprises, the knotting of a pair of threads and moistening of the portions of the threads which make up the knot, and then permitting the same to dry after the knot has been pulled hard and tight.

MARTIN N. NOLING.
